GAME BOARD

Roger P. Thomas, Pittsburgh, Pa.

Application March 25, 1952, Serial No. 19,036

Term of patent 3½ years

(Cl. D34—5)

To all whom it may concern:

Be it known that I, Roger P. Thomas, a citizen of the United States of America, residing in the city of Pittsburgh, county of Allegheny, and Commonwealth of Pennsylvania, have invented a new, original, and ornamental Design for Game Board, of which the following is a specification, reference being had to the accompanying drawing, forming part thereof, wherein:

The figure is a plan view of a game board embodying my new design.

The game board is of conventional thickness, and the essential features of my design are shown in full lines.

I claim:

The ornamental design for a game board, substantially as shown and described.

ROGER P. THOMAS.
